(57) **CLAIM**

I claim the ornamental design for the improved replacement
sprinkler head installation tool, as shown and described.

DESCRIPTION

FIG. 1 is a three dimensional view of an improved replacement
sprinkler head installation tool showing my new
design;

FIG. 2 is a top view thereof;

FIG. 3 is a bottom view thereof;

FIG. 4 is a side elevational view from one side thereof, the
other side elevational view being a mirror image of this
Figure;

FIG. 5 is an end elevational view from one end thereof; and,
FIG. 6 is an end elevational view from the other end thereof.
